(57) **CLAIM**

The ornamental design for a sun protection sleeve, as shown and described.

DESCRIPTION

FIG. 1 is a front perspective view of a sun protection sleeve in an unfastened configuration according to my new and ornamental design;

FIG. 2 is a rear perspective view thereof;

FIG. 3 is a front view of the sun protection sleeve shown in a fastened configuration on a user;

FIG. 4 is a rear view thereof;

FIG. 5 is a right side perspective view thereof;

FIG. 6 is a front view of the sun protection sleeve shown in a fastened configuration on a user in another position of use;

FIG. 7 is a rear view thereof;

FIG. 8 is a top perspective view thereof; and,

FIG. 9 is a bottom perspective view thereof.

Each of the FIGS. 1-9 depict the sun protection sleeve as worn by a user. The broken lines showing a user in FIGS. 3-9 are included for the purpose of showing environment and form no part of the claimed design. The broken lines shown in FIGS. 2 and 9 showing portions of the sun protection sleeve form no part of the claimed design.
